UNITED STATES PATENT OFFICE.

JOHN L. SOMMER, OF NEWARK, NEW JERSEY, ASSIGNOR TO J. L. SOMMER MANUFACTURING CO., A CORPORATION OF NEW JERSEY.

COAT-HANGER.

1,097,889.

Specification of Letters Patent. Patented May 26, 1914.

Application filed February 14, 1911. Serial No. 608,614.

To all whom it may concern:

Be it known that I, JOHN L. SOMMER, a citizen of the United States, residing at Newark, in the county of Essex and State 5 of New Jersey, have invented certain Improvements in Coat-Hangers, of which the following is a specification.

The present invention relates to an improved coat hanger which embodies novel 10 features of construction whereby it will form a rigid support for a coat or similar garment when extended, but which may be very compactly folded when not in use.

Among the objects of the invention are to 15 provide a coat hanger which can be instantly extended for use or collapsed without the necessity of making any preliminary adjustments; to produce a folding coat hanger which is susceptible of being properly shaped to fit a coat or similar garment cut high in the neck; to provide a simple and cheap construction, and to obtain other 20 advantages and results, as may be brought out in the following description.

25 In the accompanying drawings, in which like numerals of reference indicate corresponding parts throughout the several views, Figure 1 is a side elevation of a coat hanger constructed in accordance with the present 30 invention, the arms being shown in an extended position. Fig. 2 is a similar view showing the arms in a folded position. Fig. 3 is an enlarged side elevation of the joint between the arms and the lower end of the 35 hook member, and Fig. 4 is a transverse sectional view on the line 4—4 of Fig. 3, looking in the direction of the arrow.

Specifically describing the present embodiment of the invention, the numerals 1 40 designate a pair of arms which have their inner ends pivotally connected by means of a pin 2 to the lower extremity of a supporting member 3, the said supporting member being shown in the present instance as having 45 the form of a hook. When the coat hanger is extended, as shown in Fig. 1, the arms 1 project in opposite directions from the hook 3 so that a coat or similar garment can be hung thereon in the usual manner, 50 the outer ends of the arms being transversely looped as indicated at 4 to form a broad support for the shoulders of the coat. The arms 1 are pivoted to the hook 3 on 55 opposite sides thereof and the said hook is preferably flattened so as to be received be-

tween the arms when the hanger is folded, as indicated in Fig. 2. The inner extremities of the arms 1 are flattened and formed with the lateral extensions 5 which, as indicated in Figs 1 and 3 are designed to extend upwardly along opposite sides of the shank of the hook 3 when the coat hanger is open for use, the said lateral extensions being formed with the shoulders 6 which engage opposite sides of the hook 3 to limit 60 the downward movement of the arms and hold the arms rigidly in position when a coat or other garment is applied to the hanger. The flattened lateral extensions 5 are preferably offset inwardly from the axes 65 of the arms 1 so that the inner faces thereof are flush with the inner sides of the arms, thereby providing a construction which prevents the arms from abutting against the hook member and interfering with the 70 proper folding of the hanger. By reference to Fig. 4, it will be observed that the two arms 1 are arranged in spaced planes with the flattened hook member 3 interposed 75 between the same, and when it is desired to fold the hanger, it is merely necessary to swing the arms 1 upwardly until the looped portions 4 at the outer ends thereof are brought into contact with each other, the hook 3 being received between the arms 1 80 and the curved portions at the inner ends 85 of the arms overlapping. In this connection, it may also be noted that the hook member 3 terminates slightly below the pin 2 so as to provide ample clearance for the 90 shoulders 6 when the arms 1 are swung upwardly to collapse the coat holder.

Where coats are cut high in the neck, it is necessary in order to support the same without wrinkling that the coat hanger be bulged 95 upwardly at the central portion to provide a hump, and while it has been very easy to construct a rigid coat hanger with such a hump, all folding coat hangers have been formed with arms having a uniform curve, and were a failure when used in connection 100 with coats cut in this manner. With the present construction of coat hanger, however, the inner ends of the arms 1 can be readily curved upwardly, as indicated in 105 Fig. 1, so as to provide this central hump when the folder is extended, and this does not in any manner interfere with the compact folding of the device, since the arms 1, as previously explained, are arranged in 110

slightly spaced planes and the curved inner ends of the same overlap each other when folded.

It will be noted that the shank of the hook member is straight and that the entire hook member lies in a single plane, namely, the plane of the coat hanger, all of which conduces to simple, easy and cheap manufacture. Furthermore, the two arms 1, 1 are exact duplicates, and each may be formed at its pivotal end by a single bend and then stamping said bent end to flatten it and form the shoulder 6. This stamping offsets the pivotal end, as described, and further- 10 more widens it in the direction of strain so as to better resist such strain. The shoulders 6 thus formed are long, extending almost below the pivot 2 when the arms are extended, as shown in Fig. 3 of the draw- 15 ings, and hence they give a very strong construction which is quickly, easily and cheaply manufactured. By displacing the metal wholly from one side of the arm in such stamping, the flattened pivotal end lies 20 flush with the other side of the arm, as shown in Fig. 4 of the drawing, and hence the main portion of each arm is practically in alignment with its pivotal end, although space is provided for the two arms to pass each 25 other in folding. All of this conduces to strength and compactness of structure.

Having thus described the invention, what I claim is:

1. In a folding coat hanger, the combination of a hook member having a straight shank transversely perforated close to its end, a pin extending through said perforation and projecting at opposite sides of said shank, and a pair of arms having their adjacent ends widened in the plane of the hanger and perforated whereby said arms are pivotally mounted upon the before mentioned pin on opposite sides of the hook member, the said pivoted ends of the arms 40 extending beyond the pivotal pin and being bent each at an angle to the main portion of the arm in the plane of the hanger and provided at their facing sides with marginal shoulders adapted to engage the shank 45

of the hook member and limit downward 50 swinging of the arms when the hanger is in use.

2. In a folding coat hanger, the combination with a hook member having a straight flattened shank transversely perforated close 55 to its end, a pin extending through said perforation and projecting at opposite sides of said shank, and a pair of wire arms having their adjacent ends perforated to receive said pivotal pin on opposite sides of 60 the hook member, said ends being flattened in the plane of the coat hanger and each having its inner side or side next the shank in a plane substantially flush with the same side of the main portion of its arm, the 65 said flattened ends of the arms being extended beyond said pivotal pin each at an angle to the main portion of the arm in the plane of flattening and provided at their facing sides with marginal shoulders adapted 70 to engage opposite edges of the shank and limit downward swinging of the arms when the hanger is in use.

3. In a folding coat hanger, the combination with a hook member having a straight 75 flattened shank transversely perforated close to its end, a pin extending through said perforation and projecting at opposite sides of said shank, and a pair of arms having their adjacent ends perforated and receiving 80 said pivotal pin on opposite sides of the shank, said ends being flattened and widened each in a plane parallel to the plane of the flattened shank and extended in its said plane beyond the pivotal pin at an angle to the 85 main portion of the arm, said extensions having at their facing sides adjacent to their outer edges marginal shoulders which are farther away from the pivot pin than are the end edges of the shank, whereby said 90 shoulders engage opposite lateral edges of the shank when the arms are opened and clear the end edges of the shank when the arms are closed.

JOHN L. SOMMER.
